KEEPER DEVICE FOR DOOR LATCHES

George W. Wells, Amesbury, Mass.

Application September 26, 1935, Serial No. 42,220

3 Claims. (Cl. 292—340)

This invention relates to certain improvements in the lock mechanism disclosed in my pending application Serial No. 13,032 filed March 26, 1935, and more particularly to the striker or keeper member thereof employed in connection therewith.

Said mechanism comprises a horizontally projecting, vertically movable latch member having a jamb member engaging face on its top side, means being provided on the door for normally holding said member in a raised position in which it will engage the jamb member, said means being movable to permit said latch member to be lowered and thus disengaged from the jamb member, to permit the door to be opened.

While the jamb member disclosed in my said application operates satisfactorily, it has been found to be objectionable on account of the fact that it contained an objectionable number of parts, which unduly increased the cost of manufacture and installation.

The object of the present invention is to provide a simplified form of striker or keeper mechanism for my previously disclosed latch mechanism which will be at least as effective and durable as the form previously disclosed and which will be composed of fewer parts and may be readily assembled and constructed at a reduced expense.

I accomplish this object by means of the construction hereinafter described and illustrated in the accompanying drawings, in which:

Fig. 1 is a front elevation of the latch and keeper mechanism embodying my invention.

Fig. 2 is a sectional view at line 2—2 of Fig. 1.

Fig. 3 is detail view at line 3—3 of Fig. 1.

Figs. 4 and 5 are detail sectional views at line 4—5 of Fig. 2, showing the parts in different positions.

Fig. 6 is an elevation of a portion of the edge of the door.

Fig. 7 is a detail sectional view, at line 7—7 of Fig. 6.

Figs. 8, 9 and 10 are detail views of different portions of the latch operating means.

Figs. 11 and 12 are side views of the keeper member, showing the parts in different positions.

Figs. 13 and 14 are detail views of parts of the keeper member.

In the drawings, a portion of a door 14 and its jamb 16 are indicated, and, as it will be understood that the door swings horizontally on hinges in the usual manner, further illustration thereof will be unnecessary.

The door is provided with the usual channel shaped metal edge pillar 18 and the latch operating means are mounted on a similarly shaped metal casing 20, which is fitted into and secured to the inner side of said pillar.

A rigid, rectangularly shaped projection 22 is permanently connected by welding to the middle portion of casing 20 and extends through a similarly shaped aperture formed in the face or middle side of the pillar 18, which forms the edge of the door, as shown in Figs. 1, 2 and 3, said projection 22 having a horizontal bottom face which is arranged to engage the supporting face of the striker casing as hereafter more fully described, so that the door will be rigidly supported thereby when closed.

The top portion of projection 22 which extends beyond the outer side of pillar 18 is cut away, forming a notch having a horizontal top face 23 and a vertical end face 24 thereon, which is approximately flush with the outer surface of the pillar 18, as shown in Fig. 1, and a recess 25 is formed in said projection which extends from the inner side of casing 20 and terminates at the front wall of said projection, said recess 25 having a semi-cylindrical bottom and vertical sides extending to the top surface 23, so that the recess 25 opens to the top side and inner end of the projection, as shown in Figs. 3, 4 and 5.

A cam shaft 26, of the same diameter as that of the bottom of said recess 25, is rotatably mounted on the bottom thereof, and one side portion of said shaft, which extends from its outer end to the face 24, is cut away to form a recess 27 therein and an approximately radially disposed cam face or shoulder 28. The inner end portion 29 of shaft 26 is rigidly connected to the middle of a flat plate 30, which is located in close proximity to the inner side of the middle or bottom portion of the casing 20, and extends at each side thereof to form a pair of oppositely extending arms, one of which is provided with a rigid lug 31 and the other of which is provided with a rigid lug 32, as shown in Figs. 1, 2, and 8.

A square shaft 34, having a handle 35 on its outer end externally of the door, is mounted in a bushing 36, which is rotatably mounted in the outer side of casing 20 (see Fig. 2) and an arm 38 is rigidly connected to the inner end of said shaft by a screw 39, said arm 38 having its end portion arranged to engage the lug 31 on plate 30, so that when shaft 34 is rotated by its handle 35, the shaft 26 will be rotated to a limited extent.

A vertically movable latch member 40 is

mounted in the notch on the top side of projection 22, and when in the lowest position thereof its bottom side rests on the face 23 and its rear edge engages the end face 24, so that it completely fills the notch, and a pair of guiding pins 42 are secured to, and project vertically from the under side of said member, said pins being slidably mounted in holes 43 formed in the sides of projection 22, so that said member is rigidly held against horizontal movement relative to said projection and is guided thereby in its vertical movements, the sides of said pins each having a flattened portion to form shoulders 44, which are arranged to engage stop pins 45 fixed in the projection 22 (see Fig. 7) to limit the upward movement of said latch member and provide a permanent connection with the projection 22. The top surface 46 of the member 48 is horizontal and extends for the length and width thereof and the under side of said member 48 has a transverse projection 48 depending therefrom having a shoulder 48 at one end, which is arranged for engagement by the cam face 28 on the shaft 26, and a concave face on its lower end, corresponding in curvature to that of the surface of said shaft, the arrangement being such that when the parts are in the position of Fig. 5 and the shaft 26 is then turned to the position of Fig. 4, pressure of face 28 against shoulder 48 will cause the latch member 48 to be raised to the position of Fig. 4, in which position the member will be rigidly supported by the shaft.

A coil spring 58 encircles shaft 26, and is connected at one end thereto and at its other end to casing 28, said spring acting to rotate said shaft in the direction first to raise the latch member from its lowest position, in which it rests on the face 23 of projection 22, to its highest position, shown in Fig. 4, and to continue the rotation of said shaft until its shoulder 28 is carried for a substantial distance beneath the projection 48, this movement by spring 58 being limited by a stop pin 51 in casing 28, which engages arm 38. (See Fig. 10.) With this arrangement it will therefore be necessary to turn the handle 35 fully half the distance through which it may be turned before the cam face 28 is moved past shoulder 48 to permit the latch member to be lowered, to the position of Fig. 5.

A supplemental means is provided for operating shaft 26 from the inner side of the door, usually termed the remote control, which comprises a dog 52, which is mounted on a pivot 53 in the inner side of casing 28 and is provided with an arm 54 which is arranged to engage the lug 32 on plate 30. A link 55 is connected to said latch by a pivot 56 and has a handle 57 thereon which projects internally of the door, (see Figs. 2 and 9), so that when the link is pulled, the arm 54 will swing the plate 30 in the direction to rotate shaft 26 to permit the latch member 48 to be lowered. The dog 52 is also provided with a tooth 58 which, when the link 55 is pushed towards the edge of the door to its fullest extent, will extend beneath the under side of plate 30, so that if it should be attempted to turn the handle 35, so as to lower the latch member, this movement will be prevented. The dog 52 thus has three positions, viz, a locking position, shown in Fig. 9, an operating position in which it has acted to lower the latch member and an intermediate position in which operation by the exterior handle 35 is permitted. A coil spring 59 encircles the shaft 34 and acts to hold

arm 38 against stop pin 51 when shaft 26 is operated by the remote control means 55.

As shown in Figs. 10 and 11 the striker member, which cooperates with the projection 22 and latch member 48 above described, comprises a 5 rectangular shaped casing 60, which is set into the jamb, and is provided with a horizontal supporting portion 61, having a downwardly inclined outer end, so arranged that the under side of the projection 22 will engage said inclined end as the door is closed, and ride up on the same, so that, when the door is fully closed, it will be firmly supported thereon, and the top face 62, of the latch member 48, will thus be held at a predetermined level with relation to the striker means now to be described.

A striker bar 62 is supported by a coil spring 63 which is attached to casing 60 and is held in a horizontal position by a pair of rigid links 64, said links being of equal length and having rounded 20 ends, which are set into correspondingly shaped recesses in the top side of the bar 62 and in the under side of the top wall of casing 60. By means of this arrangement the bar 62 is permitted to swing in a predetermined path, inwardly from 25 its initial position, shown in Fig. 11, in which the outermost end of the bar engages the front wall of the casing 60, to the position of Fig. 12, during which movement the under side of the bar is constantly held in parallel relation with the top side 30 of the supporting portion 61 of the casing 60, both surfaces being horizontal, or extending in the direction which the door swings. The under side of the bar 62 is provided with a series of sharp teeth 65, which are arranged to extend 35 obliquely inward and downward, with their edges in a horizontal plane, and also with a single stop tooth 66, which is spaced from the series of teeth, for a purpose to be explained. The spring 63, which supports bar 62, is attached to the casing 40 at a point which is nearer the outer side of the casing, than the point at which it is attached to the bar, so that, when the bar is swung inward, the spring will be stretched, and thus constantly acts to pull the bar outward, and, at the same 45 time, through action of the links 64, acts to force it downward.

With the above described construction, when the door is open and the handle 35 is released, and the handle 57 is in its neutral position, the 50 latch member 48 will be in its raised position of Figs. 4 and 11, and the striker bar 62 will be in the position of Fig. 11, in which its outer end is engaged with the outer side of casing 60. As the door is closed, the rigid projection 22 rides up on 55 the inclined outer end of the casing bottom 61, causing the latch member 48 to engage the bar 62 and push it inward and upward as the projection 22 moves onto the horizontal surface of the casing bottom, as shown in Fig. 12. In this position, the teeth 65 of bar 62 are firmly engaged with the top surface of latch member 48, and any tendency of the door to move towards open position will cause the teeth 65 to bite into the top surface of member 48, so that the resulting clutch 66 action will hold the door against any opening movement. While this clutch action would take place if the spring 63 were not effective to hold the bar 62 firmly against the top face of the latch member in all closed positions of the door, the 70 presence of the spring makes the bar 62 instantly effective in clutching the latch member, so as to lock the latter against outward movement. It is to be noted in this connection that the door will be firmly locked against opening movement in a 75

multiplicity of positions or in any of its closed positions, after the projection 22 passes onto the horizontal portion of the supporting portion 61 of the casing 60.

5 When the door is to be opened, either handle 35 or 57 will be moved so as to rotate cam shaft 26 sufficiently to permit the latch member 40 to move downward to the position of Fig. 5, so that the member will be disengaged from the striker bar. In case a handle is moved by accident to a sufficient extent to turn the shaft 26 far enough to permit the latch member to be temporarily disengaged from the striker bar and thereby permit the door to move towards open position, if 10 the handle is immediately released, the outer tooth 66 will engage in a notch 67, formed in the top surface of member 40, so that the door will be prevented from opening further, as indicated by the dotted line position of Fig. 12. The handle 15 must, however, be moved to a considerable extent to turn the shaft 26 far enough to permit the member 40 to be lowered at all. It will be noted that the lowest position to which the bar 62 can move is indicated in Fig. 11, in which position 20 the links 64 are perpendicular thereto and at which point further outward movement of the bar is prevented by its engagement with the front side of the casing. The member 40 is, of course, lowered sufficiently to be disengaged from bar 62 25 when in this position.

In practice the striker bar 62 is made of hardened steel, while the latch member 40 is made of comparatively soft steel, so that the teeth 65 will effectively bite into the surface of the latch member in the closed position of the door. The construction will, however, be operative if the teeth 65 were omitted, and the bottom surface of the bar made smooth.

With the above described construction, when 40 the door is in closed position, the greater the tendency to force the door open, the greater will be the force of engagement of the striker bar with the latch member, so that all tendency to force the door open will be effectively resisted. 45 The door will also be firmly locked against opening movement in any of its closed positions, after the projection 22 rides up on to the horizontal portion of the support 61, in which position the door will be rigidly supported even though it has 50 not been closed to the fullest extent possible.

I claim:

1. A keeper for use on the jamb of a door comprising a striker bar having a horizontally disposed face on its bottom side, a pair of rigid links pivotally engaged at their lower ends with said bar and at their upper ends with the jamb, 5 the face of said bar being arranged for engagement with the top face of a latch member mounted on the door and said bar being arranged to move inwardly and upwardly when engaged by said latch member during the closing movement 10 of the door, and being spring actuated to move oppositely to lock the latch member against outward movement, the downward and outward movement of said bar being limited to permit the latch member to be lowered out of engagement therewith. 15

2. A keeper for use on the jamb of a door comprising a casing, a pair of rigid links pivotally engaged at their upper ends with said casing, and having means at their lower ends arranged for 20 engagement with the horizontally disposed top face of a latch member projecting from the door while held at a predetermined level, said links being arranged to swing inwardly from an approximately vertical position to permit closing 25 movement of the door and being spring actuated to swing outwardly to cause a clutch engagement between said means and latch member by the thrust action of the links, to lock the door against opening movement. 30

3. A keeper for use on the jamb of a door comprising a casing having a horizontally disposed supporting face arranged for engagement by a rigid projection on the door, to support a latch member thereon with its top face at a predetermined level, a rigid link pivotally engaged at its upper end with said casing and normally depending approximately vertically therefrom directly over said supporting face and having means at 35 its lower end arranged for engagement with the 40 said top face of the latch member, said link being arranged to swing inwardly from its normal position when engaged by the latch member on closing movement of the door and being actuated to swing outwardly to cause a clutch engagement 45 between its said means and said latch member top face, to lock the door against opening movement while the latch member is supported at said level. 45

GEORGE W. WELLS. 50
